DESIGN FOR A RADIO PROGRAM PRESELECTOR

Freeman H. Owens, New York, N. Y.

Application July 26, 1947, Serial No. 140,540

Term of patent 14 years

(Cl. D26—14)

To all whom it may concern:

Be it known that I, Freeman H. Owens, a citizen of the United States, residing at New York, in the county and State of New York, have invented a new, original, and ornamental Design for a Radio Program Preselector, of which the following is a specification, reference being had to the accompanying drawing, forming part thereof.

The single figure in the drawing is a perspective view of a radio program preselector embodying my new design.

I claim:

The ornamental design for a radio program preselector, substantially as shown.

FREEMAN H. OWENS.
